Attorneys.

UNITED STATES PATENT OFFICE.

CLELAND DAVIS, OF THE UNITED STATES NAVY.

ARMAMENT FOR AIRCRAFT.

Application filed November 18, 1920. Serial No. 424,979.

To all whom it may concern:

Be it known that I, CLELAND DAVIS, Commander, United States Navy, a citizen of the United States, residing at Englewood Cliffs, in the county of Bergen and State of New Jersey, have invented certain new and useful Improvements in Armaments for Aircraft; and I do hereby declare the following to be a full, clear, and exact description of the invention, such as will enable others skilled in the art to which it appertains to make and use the same.

My present invention relates to improvements in armaments for aircraft, and it is intended to provide an armament which may be quickly applied to or removed from the aircraft, and in which the guns are loaded at a fixed base and are pointed in a predetermined direction relative to the aircraft and are carried in groups without any surplus ammunition, and without the necessity of requiring gun crews to load the guns; all the work of operating the gun being to fire the gun or the battery at the proper time and when pointed in the proper direction.

To utilize aircraft to mount and operate guns of large calibre two essential characteristics are required: The guns must be of very light construction so that each machine can carry the greatest possible number of the largest caliber; and the guns must be of a type that gives no recoil on firing. These qualities are to be found, so far as now known, only in the type of non-recoil gun disclosed in my Patents Nos. 1,108,715, dated August 25, 1914, 1,108,716, also dated August 25, 1914, and entitled, Apparatus for firing projectiles from aircraft.

The effectiveness of gun fire from aircraft is limited by the fact that the speed of the machine makes it difficult to obtain more than one well aimed shot from a single gun during one passage of the machine over a target. Further, to provide gun crews and ammunition for reloading in the air would so greatly increase the weight to be carried that the number of guns in the battery would be reduced. In order to secure the greatest possible volume and concentration of fire, I propose to utilize the weight taken up by gun crews and ammunition for mounting additional guns and operate the guns as single firers, the ma-

chine to return to base after discharging its guns to replace the discharged guns by reserve guns ready loaded. Or means can be provided at the base for reloading, when the guns are demounted from the machine. 60

The method of accomplishing this is shown in the accompanying drawings, in which:

Figure 1 is a front elevation of a biplane provided with two non recoil guns of large 65 caliber detachably mounted on the front portion of the fuselage, one on either side.

Figure 2 is a side elevation of a biplane provided with a plurality of guns of smaller caliber than those shown in Figure 1, each 70 gun being separately mounted on the fuselage, and one of the guns being shown in axial section; and

Figure 3 shows a biplane provided with a battery mounted in multiple units, each 75 group of five guns being suitably secured together and securely attached to the biplane; and Figure 4 shows diagrammatically an arrangement of electric circuits for firing the guns singly, or in groups, or all together. 80

Referring first to Figure 1, A and A' indicate the upper and lower wings of an aeroplane having the central float B comprising the fuselage, and the side floats C. 85

D¹ and D² are clamping members secured at opposite sides of the fuselage, and adapted to grip the gun bodies E below the set collars e thereon. These clamping members are closed and locked by the bolts F, but 90 may be conveniently opened for the insertion or removal of the gun body after it has been loaded. The loading of the gun body should preferably be attended to at some fixed base and the guns put in place on the 95 aircraft after being loaded.

For convenience in shifting the individual guns, eyes e' may be provided to engage suitable hooks or slings (not shown).

Referring now to Figure 2, the guns E 100 are connected separately to the sides of the fuselage. I have shown in this figure five guns secured to one side of the fuselage, and there would obviously be a similar number of guns, not shown, connected to the opposite side of the fuselage.

These guns are secured in clamping members D², similar to those already described, which engage beneath the ribs or collars e on the gun body, as shown, and there being 110

practically no longitudinal thrust on the gun body when the gun is fired, the weight of the gun body taken by the annular ribs or collars e will be sufficient to hold the gun 5 firmly in place in the clamping members D^2 .

The gun bodies may be provided with eyes e' to engage hooks or slings, not shown, for convenience in lifting the gun bodies 10 and removing them from or applying them to the aircraft.

In the construction shown in Figure 3, there are two groups of five guns, each mounted on each side of the fuselage, and 15 these guns in each group are connected together by clamping tie pieces G , the upper one of which is preferably provided with eyes g for engaging lugs or slings for removing the group when desired. Each 20 group is detachably secured to the side of the aircraft by means of suitable brackets H .

All of the guns in each group are loaded at the base and the entire group is then mounted in place on the aircraft, and all 25 of the guns of each group or all the guns of all the groups may be fired simultaneously if desired.

A great variety of arrangements for accomplishing such results might be provided, 30 and I do not claim in the instant application any special apparatus or arrangement of circuits for accomplishing these results; but an arrangement of circuits for carrying out this invention is shown diagrammatically in Fig. 4, in which I have shown two groups of guns, four guns in each group and an arrangement whereby any one gun 35 may be fired, or any number in any groups, or all in one group, or some of the guns in 40 one group and some in the other group, or all the guns in both groups may be simultaneously fired.

In Figure 4 the guns of each group are indicated at E . M represents any suitable 45 source of electricity, such as the electric battery, or any electrical generator that may be carried by air craft, and used either for this purpose alone or for other purposes as well. The positive pole of this source of 50 electricity is connected to the main conductor N which in turn is connected to the guns in the right hand group by the branch conductors n . The other terminal of the source of electricity is connected by the main N' 55 and the branches n' to the guns in the other or left hand group.

Leading from the firing mechanism of the 60 respective groups of guns, which is well known in the art, are the return conductors p and p' which may be connected, respectively, to the branch conductors q and q' by means of the various switches 1 to 8. The branch conductors q are connected to the main Q , and the branches q' are connected to 65 the main Q' which are, respectively, con-

nected to the conductors Q^2 and Q^3 . The conductor Q^2 is connected to the switch 9, and the conductor Q^3 is provided with a contact q^3 adapted to engage the switch 10. These switches 9 and 10 may be simultaneously operated in any convenient way, as by means of the rod T , having the handle t , and the switches 9 and 10 are shown as engaging between the pins t' and t^2 at each end of the rod T .

The switches 9 and 10 may be disengaged from these pins and closed separately, or the two switches may be simultaneously closed by moving the rod T to the left, as shown in Fig. 4. In order to fire the guns singly, close the switches 9 and 10 and leave the switches 1 to 8 open, then by closing any one or more of these switches 1 to 8 the circuit is closed through the corresponding gun or guns, and these guns may be electrically fired.

In order to fire all of the right hand group of guns, or any number of said group, open the switch 9 and close the corresponding switches 1 to 4, and then when the switch 9 is closed the desired number of guns of the right hand group may be simultaneously fired. In a similar way, if it is desired to fire the left hand group simultaneously, or more than one of the said group, close the 95 corresponding switches 5 to 8, or as many of them as desired, meantime leaving the switch 10 open, and then close the switch 10, and electric circuits will be completed through the various guns of the left hand group, and such guns as may have their switches 5 to 8 closed will be electrically fired.

If it is desired to simultaneously fire all of the guns of both groups, close all the switches 1 to 8, leaving the switches 9 and 10 in the open position as shown in Fig. 4, and then close the switches 9 and 10, and electric circuits will be completed through all of the guns, and all of the guns may be simultaneously fired.

It will thus be seen that with this arrangement a single gun of either group may be fired, or as many guns of each group as desired may be simultaneously fired, and at the same time one or all of the guns of the other group may be fired if desired, or any one or all of the guns of both groups may be simultaneously fired.

While I have shown two groups only, it will be obvious that any number of groups 120 may be controlled by a similar system of electric circuits.

For convenience of illustration I have shown guns mounted in groups at each side of the aeroplane, but it will be obvious that the guns may be mounted in any other suitable relation with regard to the longitudinal axis of the aeroplane, and I do not mean to limit the invention to the precise arrangement or location of the guns.

It will be observed that the largest possible number of guns of a given caliber can be mounted and a maximum volume and concentration of fire obtained.

- 5 While the invention is primarily intended to apply to aircraft designed and constructed for military or naval use, it is also intended to provide an armament which may be readily applied to or detached from commercial aircraft with slight additions only to the construction of the same, which additions may be quickly made, and thus a fleet of merchant aircraft can be quickly converted into a powerful fleet of armed aircraft, ready for use for military or naval purposes.

It will be obvious that various modifications might be made in the herein described device, and in the construction, combination and arrangement of parts which could be used without departing from the spirit of my invention; and I do not mean to limit the invention to such details except as particularly pointed out in the claims.

25 Having thus described my invention what I claim and desire to secure by Letters Patent of the United States is:—

1. An armament for aircraft comprising a plurality of nonrecoil guns and means for detachably connecting said guns when loaded to the aircraft, and for removing same when desired, and means for firing said guns, substantially as described.

2. An armament for aircraft comprising a plurality of groups of nonrecoil guns, means for detachably connecting said guns when loaded to the aircraft, and for removing same when desired, and means for firing said guns, substantially as described.

3. An armament for aircraft comprising a plurality of groups of nonrecoil guns, means for detachably connecting said guns when loaded to the aircraft, and for removing same when desired, and means for firing said guns in groups, substantially as described.

4. An armament for aircraft comprising a plurality of groups of nonrecoil guns, means for detachably connecting said guns when loaded to the aircraft, and for removing same when desired, and means for simultaneously firing said guns in groups, substantially as described.

5. An armament for aircraft comprising a plurality of groups of nonrecoil guns, means for detachably connecting group units of said guns when loaded to the aircraft, and for removing said group units when desired, and means for simultaneously firing said guns in groups, substantially as described.

6. An armament for aircraft comprising a plurality of groups of nonrecoil guns, means for detachably connecting each group of said guns to the aircraft in substantially

parallel relation to each other, and for removing same when desired, and means for firing said guns, substantially as described.

7. An armament for aircraft comprising a plurality of groups of nonrecoil guns, means for detachably connecting each group of said guns when loaded to the aircraft in substantially parallel relation to each other, and for removing same when desired, and means for firing said guns in groups, substantially as described.

8. An armament for aircraft comprising a plurality of groups of nonrecoil guns, means for detachably connecting each group of said guns when loaded to the aircraft in substantially parallel relation to each other, and for removing same when desired, and means for simultaneously firing said guns in groups, substantially as described.

9. An armament for aircraft comprising a plurality of groups of nonrecoil guns, the guns of each group being secured together with their axes substantially parallel, means for detachably connecting group units of said guns when loaded to the aircraft, and for removing said group units when desired, and means for simultaneously firing said guns in groups, substantially as described.

10. An armament for aircraft comprising a plurality of nonrecoil guns, means for detachably mounting said guns when loaded in a fixed axial direction on the aircraft, means for removing same when desired, and means for firing said guns, substantially as described.

11. An armament for aircraft comprising a plurality of groups of nonrecoil guns, means for detachably mounting said guns when loaded in a fixed axial direction on the aircraft, means for removing same when desired, and means for firing said guns, substantially as described.

12. An armament for aircraft comprising a plurality of groups of nonrecoil guns, means for detachably mounting said guns when loaded in a fixed axial direction on the aircraft, means for removing same when desired, and means for firing said guns in groups, substantially as described.

13. An armament for aircraft comprising a plurality of groups of nonrecoil guns, means for detachably mounting said guns when loaded in a fixed axial direction on the aircraft, and for removing same when desired, and means for simultaneously firing said guns in groups, substantially as described.

14. A method of aerial warfare which consists in supplying a heavier than air aircraft with a plurality of loaded nonrecoil guns rigidly but detachably mounted thereon and in substantially parallel relation, and firing said guns singly or in groups.

15. A method of aerial warfare which consists in supplying a heavier than aircraft with a plurality of loaded nonrecoil guns rigidly but detachably mounted thereon, each of said guns having its axis fixed relative to the longitudinal axis of the aircraft, and firing said guns singly or in groups.

16. A method of operating nonrecoil guns from aircraft which consists in attaching 10 loaded guns to said aircraft while at rest, taking the air, firing said guns from the air, returning to base, removing the discharged guns and replacing them with loaded guns.

CLELAND DAVIS.
